ROLLER GUIDE FOR A FISHING ROD

Christ Chion, Plainview, N.Y., assignor to Allan Manufacturing Co., Hicksville, N.Y.

Filed May 10, 1965, Ser. No. 85,190

Term of patent 14 years

(Cl. D31—4)

FIG. 1

FIG. 2

FIG. 3

FIG. 4

FIG. 5

FIG. 1 is a perspective view of a roller guide for a fishing rod, showing my design;

FIG. 2 is a top view of FIG. 1;

FIG. 3 is a side view of FIG. 1;

FIG. 4 is an end view of FIG. 1, both end views being identical; and

FIG. 5 is a bottom view of FIG. 1.

I claim:

The ornamental design for a roller guide for a fishing rod, as shown and described.
